UNITED STATES PATENT OFFICE.

JOHN H. RUSSELL, OF AMSTERDAM, NEW YORK, ASSIGNOR OF ONE-HALF
TO JOHN H. GILES, OF SAME PLACE.

PAPER-FEEDING MACHINE.

SPECIFICATION forming part of Letters Patent No. 600,844, dated March 15, 1898.

Application filed February 27, 1897. Serial No. 625,346. (No model.)

To all whom it may concern:

Be it known that I, JOHN H. RUSSELL, of Amsterdam, in the county of Montgomery, in the State of New York, have invented new and useful Improvements in Paper-Feeding Machines, of which the following, taken in connection with the accompanying drawings, is a full, clear, and exact description.

My invention relates to paper-feeding machines; and the object is to provide suitable and efficient means for automatically feeding thick paper, as pasteboard or strawboard, to the folding apparatus of paper-box-making machinery.

In the drawings hereto annexed and forming a part of this specification, Figure 1 is a side elevation of my improved paper-feeding machine. Fig. 2 is an end view of the same, looking from right to left of Fig. 1. Fig. 3 is a top plan view of the machine. Fig. 4 is a sectional view taken on line $x x$ of Fig. 3. Fig. 5 is a detail view, and Fig. 6 is a sectional view taken through the center of the cross-bar.

Referring specifically to the drawings, A is a table, having four legs $a a$ and $a' a'$. Near one end of the table, below the surface and extending transversely across the same, is the driving-shaft B. Mounted on the center of this shaft to turn with it is a large roll or cylinder C, having a central peripheral groove therein for a small roller, to be hereinafter referred to. The periphery of this roller extends slightly above the surface of the table

and may be covered with felt. Above the roll C is a smaller roller C', which has its ends fulcrumed in yielding bearings working in brackets $c c$, mounted on the sides of the table. $b b$ are coil-springs above said bearings, and $c' c'$ are adjusting-screws passing through the brackets $c c$ and bearing upon the springs to regulate the pressure of the roll C' upon the paper passing between the rolls C and C'.

A sprocket-wheel D on the shaft B serves to drive the shaft at the proper speed, depending upon the speed of the folding apparatus. Another smaller sprocket-wheel E on the same shaft is connected by a chain E' with a large sprocket-wheel F, keyed to a shaft F', turning in bearings adapted to slide

in dovetailed grooves in a pair of rails G G, secured at their ends to the legs of the table.

The chain connecting the sprocket-wheels E and F is loose or of sufficient length to allow the shaft F to be moved a greater distance from the shaft E to accommodate longer sheets of paper or board when necessary.

Mounted on the shaft F', near its center, are a pair of large narrow rollers H H, separated from each other. These rollers extend a considerable distance above the top surface of the table and have at diametrically opposite points on their peripheries transverse inclined ribs d, which are stationary on the 65 rollers, and back of these adjustable ribs e are springs which serve to strike the edge of the paper or board sheet as the rolls revolve and carry it forward between the rollers C and C', which feed said sheet to the folding apparatus. (Not shown.) The rear end of the pile of paper-boards P is raised by the rolls to an inclined position, and the stationary ribs d on the rolls serve to insure the catching of the adjustable ribs against the rear edge of the 75 lower board even if it be somewhat warped, as it is liable to be. For instance, should the rear edge of the lower sheet be warped these inclined ribs d will tend to raise the depressed portion of the edge and to straighten it. By 80 simply turning the adjusting-screws f f more or less the adjustable ribs may be moved toward or from the periphery of the roll, depending upon the thickness of the sheets of paper P.

In order to provide a smooth inclined surface for the paper, a frame I, having three parallel longitudinal plates joined together at their ends, is hinged below the surface of the table between the rolls H and C and 90 held at the other end above the table by a screw g, passing through the table and bearing upon its lower side. By means of the screw the inclination of the frame I may be varied as desired. The large rolls H H are 95 moved toward and from the roll C by means of a screw J, connected with the shaft F' between the rolls H H and passing through a cross-bar K, extending between the legs $a a$ and a wheel h on the screw fulcrumed in said bar.

By locating the feeding-disks or large rolls

H H with their peripheries extending above the point of contact of the feed-rollers and also above the frame I the ribs e on the disks can easily catch the edge of the lower sheet 5 when in its inclined position on the frame. When the sheets are inclined with their rear edges raised, the lower sheet can be moved more easily by the rolls H H, and this arrangement necessitates the raising of the peripheries of the large rolls.

L L are parallel side guides for the paper, mounted upon the top of the table and adjustable toward and from each other by means of a transverse screw-shaft M below 15 the top of the table, said screw-shaft having right and left thread-engaging studs m m, extending downward from the said guides. The studs m m pass through slots i i in the top of the table. The screw-shaft M is turned 20 by means of a small wheel n on the end of the shaft at one side of the table.

Between the roll C' and the front ends of the guides L L is an upright board N, secured at its ends to the table. This board has its 25 lower edge cut away to provide a passage for the lower sheet of paper when it is forced forward by the large rolls H H. Said board N is cut away to accommodate the thickest sheets that may be fed, and in order that 30 this passage may be closed more or less I provide an adjustable sliding board or gate R, which may be raised or lowered, as desired. Said gate slides between two vertical ribs r r, secured to the board N. A screw j 35 projects from the gate through a small slot k in the board N, and upon the end of the screw and bearing upon the opposite side of the board is a thumb-nut l, which secures the gate in position. The lower end of the gate 40 is beveled, as shown in Fig. 4, so that the sheet of paper may be more easily passed through even if somewhat warped.

Directly below the board N, below the surface of the table but projecting slightly above 45 the same, is a small roller s, fulcrumed in suitable bearings. This roller decreases the friction at the commencement of the movement of the lower sheet of paper. Said roller s is located in the groove in the center of the 50 roll C.

The sheets of paper to be fed are cut to the same size and placed upon the inclined frame of the table, with their front edges bearing against the gate R. The side guides are then 55 moved together to hold the sheets in place loosely. The rolls H H are moved so that the shaft F is directly below the rear edges of the sheets P. When in operation, the rolls H H will catch and carry successively the lower 60 sheet to and between the rolls C and C', and these rolls carry the sheets to the folder of the box-making machine. Small rollers may be set in the plates of the frame I to decrease friction.

65 Having described my invention, what I claim as new, and desire to secure by Letters Patent, is—

1. In a paper-feeding machine, the combination with the table and the guides, of horizontal feed-rollers between which the sheet is passed, large rolls having catches on diametrically opposite sides, said rolls having their peripheries extending above the point of contact of the feed-rollers, and means to move the large rolls toward and from the feed-rollers, substantially as described. 70

2. In a paper-feeding machine, the combination with the table and the guides, of the horizontal feed-rollers at one end of the table, one of said rollers having its pressure adjustable toward and from the other roll, large rolls having catches, on a shaft parallel with the feed-roll shafts, the peripheries of the large rolls extending above the point of contact of the feed-rollers, gearing connecting 80 the shaft of one of the feed-rolls with the shaft of the large rolls, and means to vary the distance between the last-mentioned two shafts, substantially as described.

3. In a paper-feeding machine, the combination with the table and the guides, of the horizontal feed-rollers at one end of the table, one of said rollers having its pressure adjustable toward and from the other roll, large rolls having catches on a shaft parallel with 90 the feed-roll shafts, gearing connecting the shaft of one of the feed-rolls with the shaft of the large rolls, a screw passing between the large rolls and connecting their shaft with a cross-bar of the frame, and a wheel mounted 95 upon and turning in the cross-bar to move the screw, as set forth.

4. In a paper-feeding machine, the combination with the table and the guides, of the horizontal feed-rollers at one end of the table, one of said rollers having its pressure adjustable toward and from the other roll, large rolls on a shaft parallel with the feed-roll shafts, gearing connecting the shaft of one of the feed-rolls with the shaft of the large rolls, a screw passing between the large rolls and connecting their shaft with a cross-bar of the frame, a wheel mounted upon and turning in the cross-bar to move the screw, and an adjustable inclined frame mounted 100 on the table, as set forth.

5. In a paper-feeding machine, the combination with the table and the guides, of the horizontal feed-rollers at one end of the table, one of said rollers having its pressure adjustable toward and from the other roll, large rolls on a shaft parallel with the feed-roll shafts, gearing connecting the shaft of one of the feed-rolls with the shaft of the large rolls, a screw passing between the large rolls and connecting their shaft with a cross-bar of the frame, a wheel mounted upon and turning in the cross-bar to move the screw, a frame hinged at one end between the feed-rolls and the large rolls, and an adjusting-screw passing through the top of the table and bearing against the lower side of the opposite end of the frame, as and for the purpose described. 125

6. In a paper-feeding machine, the combi-

nation with the table and the side guides for the paper, a screw-shaft having right and leftthread passing through lugs in the guides, means to turn the screw, a board at the end 5 of said guides cut away at its lower edge, an adjustable gate to vary the size of the opening, a pair of feed-rollers in advance of the said board, the lower one having a central peripheral groove and a small roller ful-

10 crumed in bearings in said groove below the said board, as and for the purpose described.

7. In a paper-feeding machine, the combination with the table and the guides for the paper, of large rolls mounted upon a shaft, 15 said rolls having at diametrically opposite points on their peripheries inclined transverse ribs, ribs secured to the rolls adapted to be moved toward and from the periphery, and screws passing through the rims of the 20 rolls to move the said ribs, as set forth.

8. In a paper-feeding machine, the combination with the table and the guides for the paper, of large rolls mounted upon a shaft, 25 said rolls having at diametrically opposite points on their peripheries inclined transverse ribs, catches in close proximity to said ribs having spring-shanks secured to the rolls, recesses in the rims to receive the catches, and screws passing through the rims to move 30 the catches, as set forth.

9. In a paper-feeding machine, the combination with the table, guides on said table adjustable toward and from each other, a board

at the end of said guides having a recess in its lower edge, a vertically-adjustable gate on the board, a small roller below the said board, a pair of feed-rolls, one above the other, the lower feed-roll having a central peripheral groove to give space for the said small roller, the upper feed-roll being yielding and adjustable toward and from the lower roll, an adjustable inclined frame, large rollers provided with catches on their peripheries to engage the edges of the sheets, means to move the large rolls toward and from the feed-rolls, 45 guide-rails for the bearings of the shaft of the large rolls to move upon, chain-gearing connecting the said shaft with the shaft of one of the feed-rolls, and a drive-wheel on the latter shaft, as set forth. 50

10. In a paper-feeding machine, the combination with the table and the guides, of horizontal feed-rollers between which the sheet is passed, large rolls having their peripheries extending above the plane of the line of contact of said feed-rollers, suitable catches on the large rolls to engage the sheet, and means for adjusting the position of the large rolls in relation to the feed-rollers, as set forth. 55

In testimony whereof I have hereunto signed my name.
